(57) **CLAIM**

The ornamental design for a coffee brewing apparatus, as shown and described.

DESCRIPTION

FIG. 1 is a perspective view of a third embodiment of a coffee brewing apparatus;

FIG. 2 is a right elevational view of the coffee brewing apparatus of FIG. 1;

FIG. 3 is a left elevational view of the coffee brewing apparatus of FIG. 1;

FIG. 4 is a front elevational view of the coffee brewing apparatus of FIG. 1;

FIG. 5 is a rear elevational view of the coffee brewing apparatus of FIG. 1;

FIG. 6 is a top plan view of the coffee brewing apparatus of FIG. 1; and,

FIG. 7 is a bottom plan view of the coffee brewing apparatus of FIG. 1.

The broken lines in the drawings are for illustrative purposes only and form no part of the claimed design.
